UNITED STATES PATENT OFFICE

153,427

DESIGN FOR A DRESS

Fred Greenberg, New York, N. Y.

Application July 31, 1948, Serial No. 147,867

Term of patent 3½ years

(Cl. D3—26)

To all whom it may concern:

Be it known that I, Fred Greenberg, a citizen of the United States, residing in the city of New York, county of New York, and State of New York, have invented a new, original, and ornamental Design for a Dress, of which the following is a specification, reference being had to the accompanying drawing, forming part thereof.

Fig. 1 is a front view of a dress, showing my design, and

Fig. 2 is the rear view thereof.

I claim:

The ornamental design for a dress, substantially as shown.

FRED GREENBERG.
